UNITED STATES PATENT OFFICE

131,273

DESIGN FOR EMBROIDERED NEEDLEWORK FABRIC OR SIMILAR ARTICLE

Maurice Fixler, Chicago, Ill., assignor, by mesne assignments, to Fixler Bros., Chicago, Ill., a copartnership consisting of Maurice Fixler and Martin Fixler

Application December 20, 1941, Serial No. 104,749

Term of patent 7 years

To all whom it may concern:

Be it known that I, Maurice Fixler, a citizen of the United States and a resident of the city of Chicago, in the county of Cook and State of Illinois, have invented a new, original, and ornamental Design for Embroidered Needlework Fabric or Similar Article, of which the following is a specification, reference being had to the accompanying drawing, forming a part thereof.

On the drawing:

The figure is a plan view of the embroidered needlework fabric, or similar article, showing my new design.

I claim:

The ornamental design for embroidered needlework fabric or similar article, as shown.

MAURICE FIXLER.
